UNITED STATES PATENT OFFICE.

RODOLFO ROGERS, OF CULIACAN, MEXICO.

MAGAZINE PAINTBRUSH.

Application filed January 22, 1926. Serial No. 83,003.

This invention relates generally to paint brushes, the invention having more particular reference to a novel type of paint brush. The invention has for an object the provision 5 of an improved magazine paint brush which will permit of rapid painting. A further object is to provide a device of this nature in which the flow of paint, or the thickness of the coat being applied may be automatically 10 regulated. Another object is to provide a means of varying or changing the size of the brush proper or the bristles.

For further comprehension of the invention, and of the objects and advantages there- 15 of, reference will be had to the following description and accompanying drawing, and to the appended claims in which the various novel features of the invention are more particularly set forth.

Fig. 1 of the drawing is a front elevation- 20 al view of my improved suction paint brush, showing certain parts in section.

Fig. 2 is a side elevational view thereof.

Fig. 3 is a detail sectional view of a brush 25 proper, as may be used in connection with my improved device, showing a modification.

As here embodied my improved suction paint brush comprises briefly a brush head 10 having bristles 11 and one or more apertures 12 and a body 19 or container to accommodate a piston 13 or disc, being a slidable fit 30 inside the body 19 and having an extension 14 protruding through the handle 15 of the body 19.

As a means of regulating the flow of paint, I have provided a button 16 or any suitable handle attached to a rod 17 and having at 35 its lower extremity contact with a suitable lever 18 or bell crank pivoted conveniently from the body 19 as designated by the numeral 20 and making contact, at its lower extremity 21, with the slidable bar 22 having a plurality of apertures 23 to register with the apertures 24 in the cross piece 25. The 40 heretofore mentioned construction is such as will permit the apertures 24 of the cross piece 25 to be either closed, partly opened or fully opened. The springs 26 and 27 are provided to hold the pawl 28 against any 45 one of the selected notches 29, except when released by means of the protruding lever 30, the last mentioned construction being such as will hold the slidable bar 22 in any desired position. The housing 31 is of any 50 suitable design and conveniently located to

accommodate the above mentioned mechanism.

The brush head 10 has two of its opposite extremities curved upwards and inwards as designated by the numeral 32, so as to be suitably attached to the lower extremity of the body 19, said body having a plurality of apertures 33 suitably located on its bottom surface. As a means of holding the brush head 10 in position, I have provided leaf springs 34 or any similar device pivoted at 35, so as to be swung outward when it is desired to remove or change the brush head 10.

Referring to Figure 3, showing a modification of my improved device, as a means of closing, when so desired, one or more of the said apertures 33 while retaining the remaining apertures open, I have provided a second slidable bar 36 having aperture 37 and making contact with the extension 21' of the lower extremity 21 of the lever 18, which may be extended and held in place by a set screw 38 or any similar device, so that the second slidable bar may be operated, when the extension 21' is extended, by the button 16 attached to the rod 17. A substantially narrow brush head may be attached to the magazine handle in position below the apertures which are not closed by the slidable 85 bar 36.

It is obvious, that if the lower portion of my improved suction paint brush is immersed in a pot or container of paint or any liquid and the rod 14 pulled upward, that paint 90 will enter the body 19 being drawn in by the suction of the piston 13.

It is further obvious that by opening the apertures 24 that the paint thus drawn in the body 19 may be applied or spread by 95 means of the bristles 11.

It is also obvious that by means of the slidable bar 22 that the flow of paint may be regulated as desired.

It is also obvious that by changing the 100 brush head 10 that wide or narrow surfaces may be painted as desired.

It will be understood that my improved suction paint brush may be made of any suitable materials as may be required for a de- 105 vice of this nature.

While I have above described the preferred form, construction, and arrangement of the several elements employed, it will be understood that the device is, nevertheless, sus- 110

ceptible of considerable modification therein, and I therefore reserve the privilege of resorting to all such changes as may be fairly embodied within the spirit and scope of the invention as claimed.

Having thus described my invention, what I claim as new and desire to protect by Letters Patent of the United States is as follows:—

- 10 1. In a magazine paint brush, the combination of the container, a slidable valve therein for regulating the flow of paint, an extension on the slidable valve extending to the exterior of the container, an angular lever pivotally mounted on the side of the container, the lower arm of the angular lever contacting with the said extension, a spring 15 acting between the said arm and the container, normally urging the slidable valve outwardly, a casing mounted on the side of the container, a rod slidably mounted in the casing, a collar on the rod positioned within the casing, a spring disposed around the rod between the collar and the bottom of the casing, normally urging the rod in one direction, the lower end of the rod being extended through an opening in the casing and engageable against the upper arm of the angular lever, a pawl pivotally mounted on the 20 rod, a rack rigidly mounted on the side of the container, and the pawl normally engaging the rack, to hold the rod in adjusted position against the action of the spring disposed around the rod, and abutting the 25 second mentioned arm of the angular lever, to hold the first mentioned arm of the angular lever, and the connected extension in adjusted position against the action of the 30 35

spring acting against the said first mentioned arm.

2. In a magazine paint brush, the combination of a container, a slidable valve therein for regulating the flow of paint, an extension on the slidable valve extending to the exterior of the container, an angular lever pivotally mounted on the side of the container, the lower arm of the angular lever contacting with the said extension, a spring 40 acting between the said arm and the container, normally urging the slidable valve outwardly, a casing mounted on the side of the container, a rod slidably mounted in the casing, a collar on the rod positioned within the casing, a spring disposed around the rod between the collar and the bottom of the casing, normally urging the rod in one direction, the lower end of the rod being extended through an opening in the casing and engageable against the upper arm of the angular lever, a pawl pivotally mounted on the 45 rod, a lever for moving the pawl, protruding from the pawl, a rack rigidly mounted on the side of the container, and the pawl normally engaging the rack, to hold the rod in adjusted position against the action of the 50 spring disposed around the rod, and abutting the second mentioned arm of the angular lever, to hold the first mentioned arm of the angular lever, and the connected extension in adjusted position against the action of the 55 spring acting against the said first mentioned arm.

In testimony whereof I have affixed my signature.

RODOLFO ROGERS.
